BOTTLE PACKING MACHINE WITH FLIGHT CONVEYER FOR RECEIVING SUCCESSIVE ROWS OF ARTICLES

Arthur E. Rideout, Chicago, Ill., Kaye B. Holstebroe, Gildersleeve, Conn., and Albin L. Johnson, Chicago, Ill., assignors, by mesne assignments, to Emhart Manufacturing Company, a corporation of Delaware

Application July 31, 1948, Serial No. 41,754

5 Claims. (Cl. 226—14)

1

This invention relates to case packing machines and especially to machines for packing articles such as jars, bottles, and the like, in shipping cases, including cartons made of corrugated board, fiber board or similar material, the purpose of the invention being to provide an improved packing apparatus of this kind.

It is also an object of the invention to provide an apparatus which is capable of successfully handling fragile articles, such as jars containing food products or the like, and bottles filled with a liquid food product or beverage, and which will place such articles in shipping cases with a minimum of breakage.

Another object of the invention is to provide an apparatus of this kind which is rapid in operation, as well as being reliable and requiring little attention or servicing.

A further object of the invention is to provide such an apparatus which is adaptable to different plant conditions and which can be easily changed or modified to suit the particular conditions in a packing plant.

The invention will be set forth in connection with the following description of the particular embodiment of the invention which is shown in the accompanying drawings by way of example. In these drawings:

Fig. 1 is a horizontal section of the article packing apparatus taken on line 1—1 of Fig. 2;

Fig. 2 is a view showing the apparatus of Fig. 1 partly in side elevation and partly in section (see line 2—2 of Fig. 1);

Fig. 3 is a transverse vertical section taken on line 3—3 of Fig. 2;

Fig. 4 is a horizontal view taken on line 4—4 of Fig. 3;

Figs. 5 and 6 are detail views of the gate-operating mechanism which is at the right end of Figs. 1 and 2;

Fig. 5 is a view in vertical longitudinal section taken approximately on line 5—5 of Figs. 1 and 6;

Fig. 6 is a plan view of the parts shown in Fig. 5 and also showing in horizontal section a portion of the apparatus at the right end of Figs. 1 and 2;

Fig. 7 is a diagram of electrical connections;

Fig. 8 is a detail section of certain parts shown in Fig. 3; and

Fig. 9 is a fragmentary vertical section taken on line 9—9 of Fig. 2.

Referring now to these drawings, the apparatus is supported by means of a frame-work consisting of two longitudinal side frame members 1 which are supported on two pairs of uprights 2 and 3, these being connected midway of their

2

height by horizontal frame members 4, one on each side of the apparatus. These parts, for simplicity of illustration, are shown as steel castings, but, if desired, may be made of rolled steel sections suitably joined together by bolts or welding. The frame members of each side of the machine are interconnected by suitable cross or tie bars, one of which is shown, for example, at 5 in Fig. 1.

10 The two side frame members 1 project to the left beyond the two uprights 2 in an overhanging position as shown in Fig. 2 in order to provide free access to a vertically shiftable table 6 for supporting the shipping cases or cartons (one of which is indicated at 7) to receive the charge of articles which is dropped into the case from above.

15 Table 6 is provided with a plurality of rollers, one of which is shown at 8, so that the loaded case may be easily moved by hand off the table. Table 6 is mounted at the top of a vertically movable bar or plunger 9 which moves in a vertical guide-way 10, secured to a frame structure 11 which projects to the left of uprights 2 at about the height of intermediate frame members 4. The weight of table 6 and the loaded carton is counterbalanced by a weight 12 which is adjustable on the rear portion of a lever 13 which is pivoted at 14 between the two uprights 2 and is connected at its forward end through a chain 15 to the lower end of plunger 9. Since the weight 12 will overbalance the system before case 7 is loaded, latch 16 is arranged on a vertical lever 17 which is pivoted at its lower end at 18 to the machine frame. Latch 16 is biased into engagement with table 6 by means of a tension spring 19 so that the latch automatically engages the table when the table is moved to its lowermost position. Latch 16 is released by means of a foot lever 20.

20 The articles to be packed, such as the jars 21, are collected in a load-forming enclosure which is indicated generally by numeral 22 in longitudinal and transverse rows conforming to the size of the shipping case. In the embodiment illustrated, case 7 is arranged to receive twenty-four of these jars in six rows of four jars each. After a complete charge has been collected in load-forming enclosure 22, table 6 is raised to elevate case 7. In its elevated position, case 7 encloses a group of twenty-four discharge chutes 23, one row of which is shown in Fig. 3, each discharge chute having four spring fingers 24 at the bottom to brake the descent of the individual jars through the chutes and to guide them into

25

45

50

55

the individual compartments in case 7 formed by crisscross partitioning 25.

Load-forming enclosure 22 comprises the first four rows from the left as shown in Figs. 1, 2 and 4. The jars 21 are advanced toward the load-forming enclosure riding on a series of spaced parallel stationary rails 26. There are six of these rails 26, one for each of the six longitudinal rows within load-forming enclosure 22. These rails are rigid edgewise mounted metal strips supported on two cross rods 27 and 28 (Fig. 2), which extend between the two side frame members 1 and are secured to the inner surface thereof by suitable brackets. To maintain the jars in upright position on rails 26, stationary guides 29 are provided for each of the six rows of jars.

Guides 29 are comparatively wide metal strips (Figs. 2 and 9) and are supported in any appropriate manner on the side frame members 1 in fixed and rigidly spaced relation to one another. The upper edges of these guides are preferably near the tops of jars 21. The surfaces of rails 26 are preferably slightly below the bottoms of guides 29. The jars slide on rails 26 up to the left hand side of load-forming enclosure 22, and then across this enclosure to fill it. For this reason guides 29 have extensions or sections 29a which project across the load-forming enclosure. These are, in reality, continuations of guides 29.

Rails 26 also have extensions or sections 26a within the load-forming enclosure, but these sections are discontinuous and laterally shiftable into vertical alignment with the guide extensions 29a for the purpose of causing the jars 21 within the load-forming enclosure to descend through the chutes 23 and spring fingers 24 into case 7. It is only a question, however, of arranging rail sections 26a and guide extensions 29a to be laterally shiftable relative to one another, and, if desired, the reverse arrangement may be employed, that is, rail sections 26a may be continuous with rails 26, and guide sections 29a discontinuous with guides 29 and laterally shiftable into vertical alignment with the rail sections. Such a construction is shown, for example, in Patent No. 2,219,827, granted October 29, 1940 to W. D. Kimball and Cornelius I. Braren, and assigned to the same assignee as the present application.

In order to render rail sections 26a shiftable, as referred to above, they are mounted between two parallel cross bars 30 and 31 (see Figs. 3 and 4) and form a rigid, unitary structure. The opposite ends of bars 30 and 31 are pivotally supported on pins 32 which project horizontally from the lower ends of four parallel rock arms 33. Arms 33, on the front side of the apparatus, are fixed to a longitudinal shaft 34, and arms 33, at the rear side, are similarly fixed to a shaft 35. Shafts 34 and 35 are mounted for rocking movement at the upper ends of brackets 34a which extend upwardly from frame members 1. This shiftable structure is biased toward the left, as shown in Fig. 3, by means of a tension spring 36 thereby normally maintaining rail sections 26a in position to support jars going into the load-forming enclosure. The structure is moved in the opposite direction to align sections 26a with guide extensions 29a and cause the descent of the charge into the case, by means of a solenoid 37 which has a plunger 38 connected by linkage 39 to the lower end of one of the rock arms 33. An adjustable stop screw 40 is arranged on linkage 39 to bring about accurate registry of the rail and guide sections.

For the purpose of moving the jars of the six rows along their respective rails 26 and into the load-forming enclosure, a flight conveyer indicated generally by numeral 41 is employed. This conveyer comprises a pair of endless chains 42 on opposite sides of the machine as shown in Fig. 1 and trained at the right end around a pair of driving sprockets 43, and at the left end around a pair of idler sprockets 44. Driving sprockets 43 are keyed to a driving shaft 45 which is rotatably supported in suitable journals which are mounted near the right end of a pair of side bars 46. Side bars 46 are supported on two pairs of brackets 47 which are mounted on the right hand portion of frame members 1. The left hand portions of bars 46 overhang the load-forming enclosure 22. Shaft 48 which supports the idler sprockets 44 is journaled at the left ends of bars 46.

Between the two chains 42 of the flight conveyer there extend a plurality of equally spaced flight members 49 in the form of thin but stiff metal plates which are appropriately secured at their base edges to small bars 50 secured in any suitable manner at their opposite ends to the two chains 42. Flight members 49 are notched at their lower edges as indicated at 51 in Fig. 8 to provide extensions or tab portions which project below the upper edges of guides 29 as the flights travel along the lower reach in order to engage the midsections of the jars and push them along rails 26 without tipping.

It will be understood that the lower sides of the flight chains 42 are supported to make them travel in a straight line so that the ends of the notches 51 (Fig. 8) will not ride in frictional engagement with the tops of guides 29.

The jars to be packed are fed in between one or more of the spaces between flight members 49 at a point outside of the load-forming enclosure, for example, the first two rows or spaces at the right of the apparatus near driving shaft 45. At this position the flight plates have completed the rounding of sprockets 43 and are in parallel relation as shown in Fig. 2. The jars are brought up to the apparatus on a conveyer belt 52 (Fig. 1), preferably in a single line between guides 53. The jars are divided from a single line into two lines or lanes 54 and 55 which are arranged between a set of three guides 56. This dividing may be accomplished by any suitable mechanism, for example, the two star wheels 57 and 58. It will be understood that conveyer belt 52 is continuously driven by any suitable means (not shown) and that star wheels 57 and 58 are mechanically interconnected by suitable mechanism (not shown) by means of which the recesses of the star wheels are maintained in the staggered relation shown. The jars ahead of the star wheels, are in close formation as shown but leave the star wheels in spaced relation and staggered with respect to one another in the two lanes 54 and 55.

Conveyer belt 52 extends beneath the flight conveyer 41 and is trained around an idler pulley 59 at the rear side of the machine. The belt is supported on two horizontal metal strips 60 beneath flight conveyer 41 which maintain the surface of the belt level with the tops of rails 26, the belt being located closely adjacent the right ends of these rails (Fig. 2). The three guides 56 are in alignment with the three flight plates 49 by which the two intake or end rows of the jars within flight conveyer 41 are formed. However, between the ends of guides 56 and the front ends

of these three flight plates 49 is a gate mechanism which is indicated generally by numeral 61. This mechanism comprises three short guide sections 62, whose length corresponds approximately with the diameter of the jars. Guide sections 62 are secured firmly at their upper edges to a laterally shiftable bar 63.

Bar 63 is arranged to slide in two brackets 64 which are bolted to the underside of the front frame member 1. When gate mechanism 61 is shifted to the left, as shown in Figs. 5 and 6, the guide sections 62 are shifted to the centers of the two lanes formed between guides 56 and stop the further advance of jars on conveyer belt 52. The two jars opposite sections 62 are shifted laterally with the gate mechanism, and in order to support the left hand jar, a plate 65 is mounted adjacent the left edge of belt 52 (Fig. 5). Gate mechanism 61 is shifted to the left by means of a solenoid 66 having a plunger 67 which is connected to bar 63 by link 68. The gate mechanism is shifted in the opposite direction by means of a compression spring 69 arranged between the right hand bracket 64 and a collar 70 on the right end of bar 63.

The flight conveyer 41 is advanced in a step by step movement to move the jars from conveyer belt 52 forward onto rails 26, and at the same time to advance a similar number of rows of jars 21 into the load-forming enclosure 22. The mechanism for causing this step by step motion of the flight conveyer is shown in Fig. 2 and comprises a one-revolution clutch indicated generally by reference numeral 71 and which serves to turn driving shaft 45 in a clockwise direction by means of a chain 72. Chain 72 passes around a small sprocket (not shown) which is keyed to the rear end of the clutch shaft 73, the upper end of the chain passing around a large sprocket 74 which is fixed to the rear end of driving shaft 45.

Turning loosely on clutch shaft 73 in front of the sprocket just referred to there is a combination sprocket and toothed gear member 75 which is driven continuously by means of a chain 76 from the slow speed shaft 77 of a speed reducer 78. The high speed shaft of speed reducer 78 is driven by means of an electric motor 79.

Keyed to the clutch shaft 73 in front of member 75 there is a clutch driving member 80 which is a double armed member having a backlash arm 80a projecting at an angle of about 120° from the main arm of the driving member. Pivoted at 81 near the end of the main arm of driving member 80 is a driving dog 82 which is spring biased into engagement with the teeth of member 75 and which is provided with a tail portion 83 adapted to be engaged by a control arm 84 having a roller at its end.

Control arm 84 is shifted into and out of the path of tail 83 of the dog by means of a solenoid 85 having a plunger 86 which is connected through a toggle linkage 87 to control arm 84. When control arm 84 is moved to the left, it releases tail 83 and allows the biased dog 82 to engage one of the teeth of continuously rotating member 75. This connects member 75 with shaft 73 and the movement of flight conveyer 41 commences. If solenoid 85 is deenergized before driving member 80 makes a complete revolution, control arm 84 will be moved back into the path of tail 83 of the control dog and cause shaft 73 to cease rotating at the end of one revolution, the parts stopping in the same position in which they are illustrated in Fig. 2. At the moment of stopping, dog 82 is withdrawn from member 84 and 75

a spring biased arm 88 snaps behind backlash arm 80a. Arm 88 is mounted on a stud 89 attached to the frame and biased by means of a coil spring 90. A stop pin 91, also on the frame, engages a tail portion of arm 88 to limit its movement.

In the embodiment shown, in which the intake conveyer delivers two rows of articles to the flight conveyer 41 simultaneously, a single step movement of the flight conveyer must carry the flight plates 49 forward the distance of two flight spaces, or one-quarter of a revolution of shaft 45. Hence, the gear ratio between the sprocket on clutch shaft 73 and sprocket 74 is 4 to 1. It will be understood that this ratio can be changed merely by changing the size of the sprockets used so as to suit any plant conditions as to the delivery of the articles to the apparatus. In some instances, it may be desirable to deliver only a single row to the conveyer 41 and in other instances, two or possibly four.

The control of the advance of flight conveyer 41 is accomplished by means of a pair of detector switches 92 which are actuated by the foremost articles in each of the two rows entering the machine on conveyer 52. Similar switches 93, six in number, are actuated by the foremost jars 21 in each of the six rows in the load-forming enclosure. A switch 94 is actuated by a rod 95 which is attached to the case supporting table 6, the switch being closed only when the table has reached its uppermost position thereby preventing the operation of the apparatus until the case is correctly positioned to receive the charge.

Referring to the connection diagram, Fig. 7, the operation of the apparatus will now be described in connection with a further description of the control mechanism of the apparatus. Switches 92 are set so as to require the line pressure of at least six jars on conveyer 52 before they will operate. This insures that two complete rows of articles shall have been received between the three flight plates 49 at the right end of the machine before the flight conveyer 41 is advanced. The closure of these switches 92 closes a circuit from one of a pair of supply conductors 96 through the contacts of switches 92 to a conductor 97. From conductor 97 one circuit is closed through a conductor 98, solenoid 66 which operates gate mechanism 61 and back to the other supply conductor through wire 99. This closes gate mechanism 61 and stops the further advance of jars into the flight conveyer 41.

55 The energization of conductor 97 also closes a circuit through solenoid 85 which controls the one-revolution clutch 71. This circuit is from conductor 97 through a pair of normally closed contacts 100 associated with one of the switches 93, thence to solenoid 85, thence through conductor 101 to the other supply conductor 96. In order to delay the movement of the flight conveyer 41 until after gate 61 has been closed so as to insure that the supply of articles is cut off before the flight conveyer commences to operate, a dash pot mechanism 102 may be connected with the operating linkage between plunger 86 of solenoid 85 and the control arm 84 of one revolution clutch 71.

70 Clutch 71 now makes one complete revolution, the circuit through solenoid 85 being opened by the initial movement of the flight conveyer 41 which moves the jars off conveyer 52 and onto the right hand end portions of rails 26. As soon as the jars leave their initial positions on

conveyer 52, the switches 92 are released and their contacts opened. This opens the circuit through solenoid 85.

In order to hold gate mechanism 61 in the closed position after contacts 92 have opened, a mechanical latch 103 is arranged to engage the left hand end of operating bar 63 of the gate mechanism and hold the gate mechanism closed. Latch 103 is pivoted at 104 to a small bracket mounted on the bottom of the front bar 46. The latch is released by means of a release lever 103a to which a biasing spring 105 is attached which urges the latch towards engaged position. Release lever 103a is lifted toward the end of the movement of flight conveyer 41 by means of one of the four fingers of a star wheel 106 which is fixed so as to rotate with conveyer driving shaft 45. The arrangement is such that release lever 103a is lifted momentarily by one of the fingers of star wheel 106 substantially at the end of the movement of the flight conveyer. This releases latch 103 and causes gate mechanism 61 to return to open position so that the jars again commence to feed into the two empty lanes at the right end of the flight conveyer. The cycle just described is then repeated to cause another step movement of flight conveyer 41 and this places a complete charge of articles in the load-forming enclosure 22.

The presence of a complete charge in the load-forming enclosure causes the actuation of all of the six switches 93 so as to close their normally open contacts. This closes a circuit from one of the supply conductors 96 through a conductor 107, solenoid 37, a conductor 108, the contacts of the six switches 93 in series, a conductor 109 to the contacts of switch 94. As soon as the case supporting table 6 is raised, the contacts of switch 94 will be closed and the circuit will be completed to the other supply conductor 96. Thereupon solenoid 37 will cause the supporting rail sections 28a (Fig. 3) to shift to the right and cause the charge of jars to be discharged downwardly into case 7.

The purpose of contacts 106 on one of the switches 93 is to make it impossible for the flight conveyer 41 to be advanced by the one revolution clutch mechanism 71 when a complete charge of articles has already been moved into the load-forming enclosure 22.

The invention has been described in connection with only a single embodiment, but it will be understood that changes can be made in the construction and operation of the apparatus without departing from the spirit of the invention. As one example of such changes it may be stated that the gate mechanism 61 may be operated mechanically instead of electrically. The same is true, also, of the mechanism for shift-

ing the rail sections 28a in order to allow the charge of articles to drop into the case. The scope of the invention is therefore considered to extend to such constructions as may fairly come within the meaning of the appended claims.

We claim:

1. In an article packing machine, a load-forming enclosure, a case support therebeneath, an article support at one side, guides for maintaining articles on said article support in a plurality of rows lengthwise of said support, a flight conveyer arranged above said article support and load-forming enclosure, said conveyer having a series of spaced flights extending crosswise of said article support and engaging the articles thereon to maintain them in crosswise rows, means for feeding successive rows of articles between said flights, means for successively advancing said flight conveyer until a full charge is contained in said load-forming enclosure, and means for causing said charge to drop into a case on said case support.

2. An article packing machine as set forth in claim 1 in which article-directing chutes are arranged beneath the load-forming enclosure to direct the individual articles into cells within the case, said article guides and said flights serving to space the articles apart both lengthwise and crosswise of the charge and place them in vertical registry with the article directing chutes.

3. An article packing machine as set forth in claim 1 in which the articles are fed between flights at a point beyond the ends of the lengthwise guides, the movement of the flights forcing the articles against the ends of said guides to space the articles apart in each crosswise row, said flights serving to space the articles apart in lengthwise rows.

4. An article packing machine as set forth in claim 1 in which the article support comprises a series of spaced parallel edgewise mounted rails.

5. An article packing machine as set forth in claim 1 in which the flights of the flight conveyer are arranged to intermesh with said article guides so as to engage the articles below the tops of said guides.
